UNITED STATES PATENT OFFICE.

ERICK SILEN, OF PRESCOTT, OREGON.

VIOLIN PIANO.

Application filed April 13, 1921. Serial No. 460,932.

To all whom it may concern:

Be it known that I, ERICK SILEN, a citizen of the United States, residing at Prescott, in the county of Columbia and State of Oregon, have invented a new and useful Violin Piano, of which the following is a specification.

This invention relates to violin pianos and is designed primarily as an improvement upon the structures disclosed in my Patents 1,045,899 of Dec. 3, 1912, 1,115,601 of November 3, 1914, and 1,238,835 of September 4, 1917.

One of the objects of the invention is to so arrange the parts of the structure as to leave room for an automatic piano player mechanism of any well known construction.

A further object is to combine with the bowing mechanism a means whereby the lower strings of the instrument will be vibrated by the ordinary piano hammers, thus to provide an accompaniment for the violin tones produced by the vibration of the strings beginning with G below middle C, it having been found impossible to produce pure violin or cello tones by the bowing of the coarse bass strings.

A further object is to reduce the number of parts of the mechanism and thereby reduce the cost of construction without sacrificing efficiency.

Another object is to utilize a motor as the sole means for operating the mechanism, means being provided for rendering the motor noiseless.

A still further object is to provide bowing mechanism in the form of a complete unit which can be removed readily from or placed in the piano without removing any of the other actions in the instrument.

Another object is to provide improved means for applying rosin to the bowing disk whereby the supply of rosin is kept for a longer period than has heretofore been possible.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any

of the advantages of the invention as set forth in the appended claims.

In the accompanying drawings the preferred form of the invention has been shown.

In said drawings—

Figure 1 is a front elevation of the instrument the front panels being removed and certain of the parts being in section, a portion of the instrument being broken away.

Figure 2 is a section on line 2—2, Figure 1, the player mechanism being shown in elevation, the motor housing being in section and remote parts being omitted.

Figure 3 is a front elevation of the metal frame carrying the strings and sounding board.

Figure 4 is a plan view of the pedals and the adjacent portions of their connections.

Figure 5 is a section through the rosin applying device.

Figure 6 is a detail view of the supporting strip or hanger used in connection with said device, the said hanger being shown detached and open.

Figure 7 is a detail view of the upper portion of the operating rod of one of the shafts for actuating the bowing disk.

Figure 8 is a view partly in side elevation and partly in section showing the manner of mounting the shaft of the bowing disk in the instrument.

Figure 9 is a section through a portion of the bowing mechanism.

Figure 10 is an enlarged section through one of the bowing disks.

Figure 11 is a side elevation of a portion of the tremolo mechanism.

Figure 12 is a side elevation of one of the lifting rods of the tremolo mechanism, the bearing lever engaged thereby being shown in section.

Figure 13 is a detail view of a portion of the housing and the slidable arm carrying strip thereon.

Figure 14 is a plan view of a portion of the rosin applying mechanism and the adjacent disk.

Referring to the figures by characters of reference A designates the cabinet of the instrument, B the keyboard, C the strings, and D the sounding board. The wood frame carrying the sounding board D has been illustrated in Figure 3 and is designated at E. It will be noted that the metal frame

- E' has the bass strings C'' extended diagonally across the treble or violin strings C' and the wrest pins F to which the bass strings C'' are connected are located in a lower plane than the wrest pins G to which the treble or violin strings are attached so that the hammers H of the usual piano action which are used for sounding the strings C'' will strike said strings along a line indicated at h in Figure 3 while the bowing elements hereinafter described will engage the treble or violin strings C' at a higher level along the line indicated at h' in Figure 3.
- 15 The sounding board D has its front face inclined along the upper portion thereof as indicated at 1 in Figure 2 and it will be noted that the wood frame E is cut away under the marginal portion of the sounding board at the top, as shown at 2 thus to increase the vibrating area of the sounding board, there being left only a narrow shoulder 3 on the wood frame E for engagement by the upper part of the sounding board.
- 20 25 The upper bridge 4 mounted on the sounding board for engagement by the violin strings C' has one end portion carried by an extension wing 5 secured along one edge to the sounding board but spaced therefrom at its other edge where the bridge is located and as shown in Figures 2 and 3. The metal frame E' can be reenforced by a rib or brace 6 and by a supplemental brace 7 which is secured to the frame.
- 30 35 Arranged on the bottom of the cabinet A are cleats 8 on which is mounted a base strip 9, it being understood that any suitable cushioning means such as strips of felt 10 can be interposed between the cleats and the strip 9 for the purpose of absorbing vibrations. On this strip 9 are provided bearings 11 for a shaft 12 having cranks 13 whereby pitman 14 will operate the bellows 15 of pneumatic piano playing mechanism, the wind chest of this mechanism being indicated at I, the pneumatics at J and the tracker at K in Figure 2. Inasmuch as this piano playing mechanism is of the usual type and constitutes in itself no part of the present invention, it is not deemed necessary to enter into a detailed description thereof. A double pulley 16 is connected to one end of the shaft 12 while the other end of said shaft is connected by a coupling 17 of any suitable construction to a short shaft 18 journaled in one end of a housing 19' which is mounted on a base 20 supported by cleats 21. This base can likewise be provided with interposed strips 22 of felt or the like for absorbing vibrations. A gear 23 is secured to the shaft 18 and within a housing 19' and meshes with a gear 24 on a short transverse shaft 25. This shaft has a worm gear 26 which meshes with a worm 27 on a longitudinal shaft 28. Said shaft, in turn, is

coupled, as at 29, to the shaft 30 of an electric motor, one end of the shaft being journaled in a bearing 31 as shown. The casing 32 of the motor is provided with bearing sleeves 33 at the sides thereof as ordinarily and these sleeves are mounted within hangers 34 in the form of straps shaped to form loops which are suspended from eye-bolts 34'. These eye-bolts are adjustably mounted in supporting yokes or standards 35 within the housing 19. By providing hangers such as described the shaft of the motor can be relieved of all of the weight of the motor casing so that the noise which would otherwise result from the operation of the motor due to excessive vibration and friction, is eliminated and an entirely noiseless operation set up. It is to be understood that the housing 19 can be suitably lined with a sound deadening material, as shown at 36.

It is to be understood that all of the strings C'' up to G below middle C are to be vibrated by the usual hammer mechanism as heretofore indicated and which has been shown at H. The remaining strings are adapted to be vibrated by bowing disks the application of which to the strings is controlled by the keys of the keyboard B. Each key lever 37 extending inwardly from the board has a recess 38 in its upper face at the rear end thereof for the reception of the lower end of a threaded stem 39 adjustably attached to the lower end of a lifting rod 40. A link 41 is pivotally connected to this rod and to a bracket 42 secured to a rail 43 mounted within the instrument. The upper end of each lifting rod 40 is pivotally connected to a lever 44 fulcrumed as at 45 and having an upstanding spoon 46 extending in front of the lower portion of a damper lever 47. A spring 48 presses against the damper lever and serves to hold the damper 49 normally pressed against the string in the rear thereof. When the rear end of the lever 44 is swung downwardly by the elevation of the rod 40, however, the spoon 46 will press the lower end of the damper lever 47 and shift the damper away from the string C. A damper controlling plate 50 is hingedly mounted in front of the series of damper levers 47 and has a crank arm 51 to which is pivotally connected a rod 52. This rod 52 is mounted at its lower end on a crank arm 53 provided at one end of a transverse rock shaft 54 journaled on the bottom of the cabinet and beneath the strips 9 and base 20, there being a forwardly extending arm 55 upon the other end of the shaft which projects through the front of the cabinet and constitutes a pedal as shown at 56. A spring 57 extends under this arm to hold the pedal 56 normally raised. Thus it will be seen that when the pedal 56 is depressed the rod 52 will be

pressed upwardly and force the plate 50 against all of the levers 47 so as to prevent the dampers 49 from coming against the strings.

5 A cross strip 58 is arranged between and secured to the sides of a frame 59 secured in the cabinet A, this cross strip being preferably of two thicknesses as shown in Figure 2 and supporting an elongated housing 60 from the bottom of which extends a forwardly projecting flange 61'. The top of the housing has been indicated at 61 and a strip 62 is hingedly and slidably mounted on this top, the spindle 63 on which the strip is mounted being extended laterally from the housing and carrying a spring 64 bearing against an eye 65 extending from the strip 62. If preferred a pair of these springs and eyes therefor can be provided so that the strip 62 is thus normally held pressed toward the left. An antifriction roller 66 can be interposed between the strip 62 and the top 61 of the housing and a finger piece 67 can be extended upwardly from the strip 62 to enable said strip to be swung upwardly and downwardly about its hinge connection. Arms 68 are mounted on the strip 62 and are pivotally connected thereto by screws 69 or the like. Clamping screws 70 having washers 71 are extended between the ends of these arms and a rib 72 on the strip 62 and by tightening the screws 70 the washers will be clamped on the arms and the arms held against angular adjustment. The back end of the arms 68 are provided with hangers 73 one of which is shown in detail in Figures 5 and 6. Each of these hangers is formed of a strip of metal folded to V shape and having ears 74 extending at right angles from the upper ends of the hanger. A stud 75 is placed in one of the members of the hanger with its head 76 between the hangers. By then drawing the members of the hanger together, as shown in Figure 5, and with the ears 74 lapping each other, a fastening device indicated at 77 can be inserted through the ears and through the arms 68, thus holding the head of the stud 75 tightly clamped within the hanger. A disk 78 is mounted for rotation on the stud 75, being held thereto by a cotter pin 79 or the like, and in one face of this disk is provided an annular recess 80 in which is molded a ring 81 formed of rosin there being preferably provided anchoring ribs 82 on the disk for extending into the rosin to hold it properly assembled with the disk. This construction and arrangement has been clearly shown in Figures 5 and 6. For the purpose of sliding the strip 62 against the action of the springs 64, there is provided a bell crank 83 having an upwardly extended arm connected by a link 84 to the strip 62 while the lower arm of this lever has a rod 85 extending downward-

ly therefrom and bearing on a crank arm 86 extending rearwardly from one end of a shaft 87 located under the base 20. This shaft has a forwardly extending arm 88 terminating at its front end in a pedal 89 located in front of the case A, the said arm 88 being held normally raised by a spring 90. Thus it will be seen that when the pedal 89 is pushed downwardly the rod 85 will thrust upwardly against the bell crank 83 and cause said bell crank to thrust through the link 84 against the strip 62 so as to shift said strip against the action of its springs 64. The action of these springs is assisted by another spring 91 connecting the lower arm of the bell crank 83 to one side of the frame 59.

Secured to the end portions of the flange 61' are bearings 92 having sleeves 93' in which is journaled a shaft 93. Arranged on this shaft 93 so as to project between the strings C' are bowing disks 94 formed of layers of flexible material cupped as shown, the said layers of each disk being clamped together and secured to the shaft by nuts 95 screwed on the shaft. Washers 96 and 97 are interposed between these nuts and the disks, the washers 96 which engage the concave faces of the disks being smaller in diameter than the washers 97 which engage the convex faces of the disks. Thus when the nuts are tightened the disks will not tend to buckle out of shape, as often happens especially with disks of large diameters clamped between the nuts. 100

Journaled within the housing 60 are shafts 98, each shaft being offset within the housing, as shown at 99, so as to be held against longitudinal movement. The shafts extend to the spaces between the bowing disks and are provided with fingers 100 which lie close to the convex faces of the respective disks 94. A roller 101 is mounted on each of these fingers for direct contact with the adjacent bowing disk. Cranks 102 are provided at the front ends of the shafts 98 and project into rollers 103 engaging the heads of threaded stems 104 adjustably connected to rods 105. The upper ends of these rods bear against the front edge of the flange 61' and said rods also are designed to work up and down within guide loops 106 extending from the strip 58. The lower ends of the rods are pivotally connected to the levers 44. Thus it will be seen that when anyone of these levers 44 is thrust upwardly by its key lever 37, the rod 105 will rotate the crank 102 and cause the finger 100 to swing laterally so as to bring its roller 101 against the adjacent bowing disk 110 and flex it into contact with a string C'. 115

A pulley 107 is secured to one end of the shaft 93 and receives motion through a belt 108' from the double pulley 16 heretofore described. Thus it will be seen that during 120

the operation of the motor and the shaft 12 the shaft 93 will be rotated and the flexing of any one of the disks 94 against a string C' will result in the vibration of the string and the production of a tone like that given by a violin. Whenever necessary the pedal 89 can be depressed so as to apply the rosin disks to the bowing disks. Whenever the rosin disks contact with the rotating bowing disks, rosin will be applied to the friction edges of the bowing disks and at the same time the rosin disks will be rotated. As a result of this arrangement the wear upon the rosin disks will be equalized throughout the surface of the disks.

Extending through the sides of the frame 59 is a shaft 107 to which is secured a vibrator or roll 108 having longitudinal corrugations. This shaft is adapted to work within openings 109 formed in the sides of the frame 59 and is journaled in levers 110 fulcrumed on the sides of the frame as shown at 111. Springs 112 bear down on the levers 110 so as to hold the shaft 107 normally in its lowermost position, and secured to one end of the shaft 107 is a pulley 113 driven by a belt 114 extending over guide pulleys 115 and driven by the pulley 16. Notches 116 are formed in the lower edges of the levers 110 to receive the forked upper ends 117 of lifting rods 118. The lower end of one of these rods is connected to a crank arm 119 extending rearwardly from a shaft 120 arranged under the strip 9 and constituting the fulcrum of a lever 121 the front portion of which constitutes a pedal as indicated at 122. The rear arm of the lever 121 has a finger 123 extending laterally therefrom and engaged by the other rod 118, it being understood that this finger is so located as to support the two rods 118 at the same distance from the axis of rotation of the shaft 120. A spring 124 is provided for holding the pedal 122 normally elevated.

Each of the rods 105 is provided with an adjustable block 125. A rail 126 is located back of the rod and has brackets 127 on which are pivoted levers 128. One of these levers is provided for each rod 105 and each lever carries a roller 129 which overhangs and is normally spaced from the corrugated roll 108. A spring 130 has one end seated in bracket 127 and its other end bearing upwardly against the lever 128 on said bracket. Thus the lever is held pressed against a stop 131 on the bracket and with one end projecting into the path of the block 125. It will be obvious that each time the rod 105 is moved upwardly by the depression of a key 37, the block on said rod will move against the lever 128 in the path thereof and swing the roller 129 downwardly. This will not produce any results, however, unless the pedal 122 should be depressed in which event the roll 108, while rotating, would be ele-

vated so as to contact with and oscillate each roller 129 as lowered into contact therewith, thereby producing a tremolo because every time the roller 129 is pushed upwardly by the corrugated roll the lever 128 will press down on the block 125 in contact therewith and cause the flexed bowing disk to shift out of contact with its string.

Motion is transmitted to the lever 44 of each key from the piano player attachment 75 through a rod 132 extending from the pneumatics J. Thus the bowing mechanism can be operated either by hand or mechanically.

Any suitable soft pedal mechanism can be used in the instrument and as the same constitutes no part of the present invention it has not been deemed necessary to describe or illustrate it. A soft pedal has been shown at 133, the same being yieldingly supported by a spring 134 and adapted to operate the soft pedal mechanism through a lever 135.

It will be understood that by detaching the housing 60 from the frame 59 the entire mechanism mounted on said housing can be removed from the instrument.

What is claimed is:—

1. A violin piano including a sounding board having piano strings extending across one face thereof, a keyboard, hammers adjacent certain of said strings, means for transmitting motion to the hammers from certain of the keys of the keyboard, bowing disks adjacent the remaining strings, means for rotating the disks, and means operated by the remaining keys of the keyboard for shifting the disks against the adjacent strings, said hammers and bowing disks being located at the same side of the sounding board.

2. A violin piano including a sounding board having piano strings extending across one face thereof, hammers for sounding the bass strings, bowing disks for sounding the remaining strings, means for rotating the disks, keys for actuating the hammers, keys for positioning the disks against their strings, said hammers and bowing disks being located at the same side of the sounding board, and an automatic player attachment 105 for actuating both the hammers and the disks to sound their respective strings.

3. In a violin piano a bowing disk including nested cupped layers of flexible material, a shaft extending therethrough, washers upon the shaft and engaging the opposed faces of the disk, the washer engaging the convex face being of greater diameter than the other washer, and means engaging the shaft for clamping the layers between the washers.

In testimony that I claim the foregoing as my own, I have hereto affixed my signature.

ERICK SILEN.
